UNITED STATES PATENT OFFICE

JOHN J. FLANIGAN, OF OAK PARK, ILLINOIS, ASSIGNOR TO VIVID, INCORPORATED, OF CHICAGO, ILLINOIS, A CORPORATION OF ILLINOIS

DUPLICATING MACHINE

Application filed March 5, 1929. Serial No. 344,203.

My invention relates to duplicating machines and more particularly to the type of duplicating machine which employs a gelatin band on which an original imprint is first made and from which multiple impressions are then taken. In machines of this type the gelatin band is unwound from a roll and stretched over a bed plate to present different portions of its surface for printing operations. For each new imprint the band is advanced to bring a fresh portion of the band into impression position. After the band is used it is moistened and re-rolled and stored until the impression surface is renewed.

25 A primary object of the invention is to control the operation of the platen roller in a novel manner to insure perfect registration of the sheet for receiving the impression from the imprint on the band.

20 Another object is to uniformly moisten the gelatin band as it is re-wound upon its spindle.

Another object is to provide a machine which is especially effective in handling a wide range of sheet sizes from large sheets 25 to small stiff sheets such as postal cards.

30 A further object is to improve the conveyor and its operating mechanism which carries the rolls of gelatin bands whereby the rolls may be successively brought into operative position easily and without shock or liability of damage to themselves or to the mechanism.

35 A further object is to provide a structure in which the gelatin band may be properly and uniformly stretched on the printing bed and in which the tension on the band can be released before the parts are unlocked for the purpose of advancing the band.

40 Another object is to provide a light-weight platen carriage requiring very little effort to move it back and forth through impression position, which can be operated as fast as the operator desires and which will be noiseless in operation, require very little lubrication, and will not bind in its guides.

45 And a further object is to provide a duplicating machine of this character which will be simple, durable and reliable in construction and highly efficient in operation.

The accompanying drawings illustrating one embodiment of the invention,

Fig. 1 is a side elevation of the machine;

Fig. 2 is a plan sectional view on the line 2-2 of Fig. 1;

Fig. 3 is an enlarged top plan view of the platen carriage and a portion of the adjacent frame;

Figs. 4, 5 and 6 are enlarged sectional views of the platen carriage and the bed of the machine taken on line 4-4 of Fig. 3, showing the platen carriage in different positions;

Fig. 6a is a detail section on the line 6a-6a of Fig. 3;

Fig. 7 is an enlarged detail section of the front reel and driving mechanism on the line 7-7 of Fig. 1;

Fig. 8 is a transverse detail section on the line 8-8 of Fig. 7;

Fig. 9 is a detail section on the line 9-9 of Fig. 7;

Fig. 10 is an enlarged detail section on the line 10-10 of Fig. 3;

Fig. 11 is an enlarged section on the line 11-11 of Fig. 2;

Fig. 12 is an enlarged detail fragmentary view of the spindle gears, showing the automatic stop for determining position of the rolls;

Fig. 13 is an enlarged perspective of the parts shown in Fig. 12; and

Fig. 14 is a detail section on the line 14-14 of Fig. 2.

The duplicating machine which embodies my invention and which is illustrated in the drawings comprises in general a main frame A in which the conveyor B for the gelatin rolls is mounted, a bed plate frame C mounted on the main frame for supporting the gelatin printing band in printing position, and a platen carriage D mounted on the bed plate frame for movement in operative relation to the bed. The main frame is preferably made up of tubular construction and embodies the legs 1, the cross bars 2 and the side plates 3 which enclose the upper portion of the main frame, these parts being all suitably secured together to form a rigid, light-weight structure. The conveyor B is

mounted in the frame below the bed plate and it comprises two endless, flexible metal bands arranged in parallel relation and spaced apart substantially the width of the frame. These conveyor bands travel over the idler wheels or pulleys 5 supported on suitable shafts 6 journaled in the main frame. The upper wheels 7 for the conveyor bands are keyed on a transverse drive shaft 8 which is provided with peripheral teeth 9 engaging spaced openings 10 in the conveyor bands for positively driving the conveyor and maintaining definite registration of both conveyor bands. This driving means for the conveyor is operated by a hand wheel positioned just outside of the main frame. The shaft 8 is journaled in the side members 3 of the main frame and one end extends through the side member and carries the hub 11 which preferably has three handles 12 equally spaced around the hub so that one of the handles will always be in proper position to be grasped by the operator when it is desired to operate the conveyor.

25 The gelatin bands are arranged in a plurality of individual rolls 14 Figs. 1, 2, which are mounted on the conveyor and are successively brought into operative position by the movement of the conveyor. The individual rolls of gelatin bands are wound on spindles 15 spaced at equal intervals on the conveyor and their ends are mounted in small sleeve bearings 16 fastened on the conveyor bands. The spindles carry small gears 15' at their 30 corresponding ends which engage a gear 45 located in the operating position of the rolls for driving the rolls as hereinafter described. Just underneath and inside of the upper edges of the side member 3 are brackets 17 35 which are bolted to the main frame, as shown in Figs. 1, 12 and 13, and which carry pawls or latches 18 pivoted at 19 to their respective brackets.

40 These latches are positioned in the path of the spindle bearings 16 on the conveyor bands and are yieldingly pressed downwardly by the springs 20 positioned between the latches and the tops of the bracket. The latches are located in the main frame just at the rear 45 end of the bed plate frame C, and they determine the operating position for the gelatin rolls on the conveyor. The latches have on their under edges V-shaped notches 21 which engage the spindle sleeves 16. The edges 22 50 of the notches are sufficiently vertical to form steps against the spindle bearings 16 to prevent the conveyor from being moved in a reverse direction. The cam edges 23 of the notches are angled sufficiently to permit the sleeves to raise the latches and allow the spindles to ride out of the notches and pass the latches. I prefer to arrange the structure in this manner so that the conveyor will have free movement in the one direction. The 55 conveyor with a large number of rolls is com-

paratively heavy and stores up considerable momentum when operated to bring a roll into position. If it were stopped suddenly it would receive quite a shock which might result in damage. But if the operator is permitted to rotate the conveyor until the roll passes the latches he will then stop the conveyor gradually simply by ceasing to further operate it. He then reverses the movement of the conveyor until it is stopped by the notch abutment 22 and thus avoids a shock on the entire conveyor mechanism. The forward ends 24 of the latches are beveled sufficiently so that in the event the spindles pass the ends 24 the reverse movement of the conveyor will cause the latches to ride up on the spindle sleeves. The operator can tell by the click of the latches when he has reached the point for reversing the movement of the conveyor.

60 In a machine of this type the free end of the gelatin band 14 of the particular roll which has been placed in operating position, as previously described, is brought up over the rear end of the bed plate, forwardly along said bed plate to the front end thereof, and then downwardly where it is connected to a permanent winding or take-up reel 26. The free end of the band is provided with any suitable clip to engage a hook 27 on the winding reel. The winding reel is positioned in the extreme forward end of the main frame between the side members 3 thereof and below the end of the bed plate frame. This reel is preferably tubular and it is mounted on a drive shaft 28 having bearings 29 in the side members of the main frame. The shaft has a hand wheel 30 fastened at one of its ends which extends to the outside of the main frame 3 and the operating wheel has a suitable crank handle 31 for the operator. As shown more clearly in Figs. 7, 8 and 9, the reel is freely rotatable on the shaft 28 but it is supported thereon by a hollow plug member 28' which has a bearing 32 keyed therein but free on the shaft. This bearing forms one member of a clutch and is provided with teeth 32' which are engaged by corresponding teeth 33' on one end of a clutch member 33. The clutch member 33 is mounted on the shaft and is shiftable longitudinally thereof. These clutch members 32, 33, when engaged connect the reel to the shaft so that the hand wheel will be operative to rotate the reel and wind the gelatin band thereon. The clutch member 33' is moved into and out of engagement with the member 32 by means of a pin and slot connection with the shaft. As shown in Figs. 7 and 9, the shaft carries a pin 34 which operates in an angularly disposed slot 35 in the clutch member 33 to shift the clutch member longitudinally of the shaft, to the right Fig. 7, when the shaft is rotated. Since the clutch member 33 is rotatable with the shaft it is

provided with a suitable weight 36 tending to retard its rotation and thus insure a relative movement between the shaft and the clutch member. Hence when the shaft is 5 rotated in the direction to wind the band upon the reel the movement of the shaft causes the clutch member to shift into engagement with the reel member and connect the reel to the shaft. The reverse rotation 10 of the shaft will shift the clutch member out of engagement with the reel and thereby release the reel so that it will be free to rotate in the reverse direction when the gelatin band is rewound upon its spindle at the rear 15 of the machine. A bevel gear 37 Fig. 7 is loosely mounted on the drive shaft adjacent the bearing 29 and its hub extends into the end of the reel and is provided with teeth 38 which are engaged by corresponding teeth 20 39 on the other end of the clutch member 33. Thus when the drive shaft is reversely rotated by the handle 30 for the purpose of rewinding the gelatin band upon its spindle the clutch member 33 is shifted into engagement 25 with the gear to the left Fig. 7, and connects the gear with the drive shaft. The gear 37 meshes with bevel gear 40 which is keyed on the end of a long shaft 41. The forward end of this shaft has a bearing 42 30 in the bearing member 29. The shaft extends to the rear end of the frame and is mounted in a bearing member 41' fastened to the main frame. This shaft has a bevel gear 43 adjacent said bearing 41' Figs. 1, 2, 35 and 12 which drives a bevel gear 44 on one end of a short shaft 44' in said bearing member 41' Figs. 2 and 12. The other end of this short shaft has the small gear 45 previously mentioned which is positioned underneath 40 the conveyor band in the path of the spindle gears 15' for the individual rolls. When a roll is brought into operating position by the conveyor, as previously described, this spindle gear 15' is brought into meshing relation 45 with the driving gear 45 and establishes driving connection between the shaft 41 and the spindle. Thus when the drive shaft 28 is reversely rotated by the hand wheel the gears and shaft 41 are automatically 50 connected to said drive shaft by the clutch member 33, and this motion is transmitted by the shaft 41 to the spindle in a direction to rewind the gelatin band upon said roll.

55 In the operation of the machine after the gelatin band roll has been moved into position by the conveyor and the end of the band is stretched over the bed plate and connected to the reel 26, the reel is rotated in a direction 50 to wind the band thereupon for the purpose of presenting successive portions of the gelatin band on the bed plate for impression operations. During the winding of the band upon the reel the roll at the rear end is free 65 to rotate by a pull on the band itself. It is true that this roll is connected to and drives the shaft 41 and the gears 40 and 37 at the forward end of the machine, but these are also free to rotate since the clutch member 33 is at this time in the position which connects the reel to the drive shaft.

70 It is desirable to stretch the band taut upon the bed plate and to lock the roll and reel against rotation so as to eliminate any danger of disturbing the band during the printing operation. For the purpose of holding the roll against rotation I provide a brake on the shaft 41 adjacent its forward end. This brake consists of a drum 50 keyed 75 on the shaft and a brake band 51 adapted to grip the drum and hold the shaft against rotation. As shown more clearly in Figs. 7 and 8 the brake band surrounds the drum 50 and its end portions 52 are turned upwardly in substantially parallel relation. A shaft member 53 is mounted in bearings 54 in the frame member 3 and extends through transverse holes in the brake band ends 52. This shaft carries a pin 55 which acts on a beveled cam block 56 adjacent one of the ends 52 of the brake band. The shaft has a collar 57 to hold the other member 52 of the brake band. The rotation of this shaft operating on the cam 56 forces the two ends 52 of the band towards each other and causes the band to grip the brake drum. A suitable hand lever 58 on the outside of the main frame is provided for the operator. A coil spring 53' is anchored at one end to the frame, and its other end has a loop through which the shaft 53 passes, the tension on the spring being sufficient to frictionally hold the shaft in the position to which it is rotated. The inner end of the shaft 53 has a pawl 59 pivotally mounted thereon and the end of this pawl engages the teeth of a ratchet wheel 60 on the end of the reel 26. When the pawl is in engagement with the ratchet wheel the reel will be locked against reverse rotation. After the operator has wound a fresh portion of the gelatin band into impression position on the bed he throws the hand lever 58 upwardly and operates the brake to lock the shaft 41. This locks the roll against further rotation. The winding reel at the forward end, however, is still free to continue turning in a winding direction and the operator may thereby apply whatever tension on the band he desires for the imprinting and impression operations. The ratchet will hold this tension by preventing reverse movement of the reel. The pawl 59 is moved into and out of engagement with the ratchet by means of a pin 61 on the end of the brake shaft. This pin engages a pin 62 carried by the pawl itself. It is preferable to relieve the tension upon the band first, and thereby relieve any binding action on the pawl, before the pawl is lifted out of engagement with the ratchet. For this reason the pin 61 is so positioned on 130

the shaft that it will not engage the pin 62 until the brake band opens and releases the shaft 41. The tension on the gelatin band will then slightly rotate the roll and shaft 41 until the tension is relieved and the parts are free. Further movement of the hand lever 58 will then lift the pawl out of engagement with the ratchet and restore the parts to condition where the winding reel may again be operated to wind a fresh portion of the band into impression position.

The bed frame, as before mentioned, is positioned at the top of the main frame. It has a horizontally disposed bed plate 65 and two vertically disposed side members 66 having outstanding flanges at their lower edges which are secured to the upper edges of the main frame by means of the bolts 67. On the upper side of the bed plate is a fabric facing 70 forming a suitable supporting surface for the gelatin band. At each end of the bed plate is a transverse roller 71 over which the gelatin band travels.

An end margin bar frame, Figs. 3-6, is positioned at the forward end of the bed plate. This margin bar frame has a cross bar 72 extending across the bed plate frame at the forward end thereof just below the plane of the bed plate. At its ends this transverse bar has two side bars 72' positioned along the inside faces of the side members 66 of the bed plate frame just underneath the bed plate. This margin bar frame, as indicated in dotted lines in Fig. 3, is horizontally slideable towards and from the front end of the bed plate. It is supported for this purpose on headed studs 73 instanding from the side members 66. The lower edges of the frame are provided with notches 74, Fig. 4, for engagement with the studs 73 to hold the margin bar frame in either its normal position or its extended position. The frame may be shifted to either position by simply raising the outer end slightly until the notches 74 clear the studs, and then sliding the frame in either direction. The cross bar 72 carries an L-shaped member 75 fastened thereto by means of screws 76, the holes through which the screws pass being larger in diameter than the screws so that the margin bar may be adjusted on its frame. The upstanding portion of the member 76 carries the end margin or gauge bar 77. This bar is likewise L-shaped in section and, as shown in Figs. 4, 5 and 6, is mounted with its horizontal portion slightly below the plane of the surface of the gelatin band. The margin bar is positioned at a sufficient distance from the end of the bed plate so that when the sheet 78 to be printed is inserted against the bar its end will project beyond the roller 71. Ordinarily a flexible sheet will be stripped from the gelatin band, after the impression operation, by the platen and grip rollers in their

return travel, but the printed sheet may be removed by grasping the forward edge which projects beyond the roller 71 into the margin bar. The margin bar is first extended or pulled outward to give easy access to the sheet. This is especially useful when stiff sheets or cards are printed. In practice, the moving of the margin bar and removal of the sheet is usually accomplished with one hand in a quick movement.

The platen carriage D, Figs. 1, 4, 5 and 6, is mounted to move back and forth above the bed plate in operative relation thereto. This carriage comprises a flat bar 80 extending crosswise of the bed plate at a definite distance above the gelatin band with its ends 81 turned down to overhang the edges of the bed plate, Figs. 1, 10. One of these downturned ends carries a forwardly extending bracket plate 82, Fig. 1, which has guide rollers 83 mounted thereon. One of these rollers is positioned to travel along a trackway formed by the upper surface of an outstanding flange or ledge 84 of the bed plate frame, and the other roller is positioned to engage the opposite under surface of this flange. Thus the carriage is held against vertical movement with respect to the bed plate frame but is permitted free longitudinal movement thereon. The other downturned end 81 of the carriage member 80 is bolted to an elongated sleeve 85, Figs. 3, 10. This sleeve embraces a longitudinal guide rod 86 extending parallel with the bed plate frame at one side and underneath the overhanging flange 87 of said frame. The bore of the sleeve is larger than the guide rod and the sleeve carries at each end a plurality of radially disposed bearing rollers 88 grouped around the guide rod 86 and riding on said rod. I have found that by enclosing the guide rod 86 in a sheathing 89 of fiber or other suitable material as a bearing surface for the bearing rollers 88 the noise incident to the movement of the sleeve along the guide rod is lessened and that no lubrication is required on the surface of the guide rod because of the pressure of the rollers. This sleeve is of sufficient length to rigidly hold the carriage square with the gelatin band and the bed plate throughout the reciprocable movement of the carriage. The carriage bar 80 supports the sheet feed chute 90 and the yoke or frame 91 which carries the platen and grip rollers. The guide plate 92 of the chute is disposed at the proper angle to guide the sheet between the rollers as hereinafter described. The carriage yoke or frame 91 extends forwardly of the carriage bar 80 but is pivoted at 93 to the side member of the chute 90 so that the yoke may be swung upwardly, as shown in dotted lines in Fig. 1. This yoke carries a spring pressed locking pin 94 adapted to enter the holes 95 in the upper or lower posi-

tions of the carriage yoke to lock the yoke in either of its positions. By means of this construction the platen and grip rollers may be swung upwardly clear of the printing surface for the purpose of enabling the platen roller to be readily cleaned and also for the purpose of enabling especially long sheets to be removed from the printing surface. The sheet feed chute, together with the carriage yoke, is bolted, as shown in Figs. 4, 5 and 6, to the carriage bar 80, and shims 96 are placed between these two members so that the platen roller may be adjusted vertically with respect to the gelatin band. The carriage yoke 91 carries a grip roller 97 spaced a definite distance above the surface of the gelatin band and mounted on a transverse shaft 98 which is freely rotatable in bearings in said yoke. The periphery of this grip roller, as shown in Figs. 4, 5 and 6, is practically in a line extending from the inclined chute to the corner of the margin bar so that when the platen roller and the grip roller are separated as shown in Fig. 4 the sheet can be freely inserted between the rollers directly against the margin bar in a substantially straight line and without bending. The platen roller 100 which also functions as a pressure feed roller is carried by a yoke or U-shaped frame 101 which is pivotally mounted on the transverse shaft 102 in the carriage yoke 91 so that the platen roller may be swung vertically toward and from the bed plate. The ends of the platen yoke have open ended cam slots 100' Figs. 4, 5, 6 and 6a disposed at an angle and in which the ends of the platen roller shaft 103 are positioned. The platen roller is thus bodily movable in the slots but it is yieldingly held in the slots by the springs 104 which are anchored to the yoke and which bear against the platen shaft. When the platen roller yoke is swung down from up position Fig. 4 to impression position Fig. 5 the platen roller will yield in the slots as it passes the grip roller, but will be held by the cam walls 101' of the slots 100' in constant operative engagement with the grip roller. The rollers will thus grip the sheet between them and will curve the sheet to conform to the shape of the rollers. If the platen roller were allowed to rotate while it is passing the grip roller the rotation thereof would be in a direction tending to drag the sheet away from the margin bar, and each time a sheet were inserted and the platen roller brought into position the sheet would be dragged out of registration with the imprint on the gelatin band. To prevent this I provide a brake or drag 106 for the platen roller in the form of a curved spring. One end of this spring is fastened to the platen yoke and its outer end portion yieldingly bears on the end of the platen roller. This brake or drag supplies sufficient pressure to prevent the rota-

tion of the platen roller while it is passing the grip roller. Holding the platen roller against rotation in this manner causes it to act on the sheet, in its bodily movement downward, in a direction to frictionally urge the sheet toward the margin bar. The platen roller, however, is relieved of brake action just before it reaches its lowered or impression position, and when the carriage is started along the printing bed away from the margin bar the platen roller will be free to rotate in contact with the sheet and properly lay the sheet upon the gelatin band. This is accomplished by so arranging the parts that the outer end of the brake spring 106 will engage the end portion of the grip roller just before the platen roller reaches its lowered position, Fig. 5. Continued movement of the platen roller into its final impression position lifts the spring from the platen roller. The platen yoke has an upstanding handle 109, Figs. 1 and 3, in convenient position for the operator to operate the yoke and the carriage in one continuous operation.

In practice the operator moves the carriage toward the front end of the bed plate until it is brought into starting position shown in Fig. 4, swings the platen roller upwardly by means of the handle 109 and inserts a sheet of paper diagonally downward between the grip and platen rollers and into engagement with the margin bar. He then swings the platen roller downward into operative position, Fig. 5, and when this movement is completed further pressure on the handle starts the carriage moving away from the margin bar. This is generally done in one quick motion. The pressure which the platen roller exerts upon the sheet is determined by the pressure which the operator applies to the handle. The carriage yoke 91 has stop lugs 110 at its ends positioned to engage the lower edges of the platen yoke, Figs. 4, 6. These stops allow the platen roller to be firmly pressed upon the paper but they limit the movement of the yoke at such a point as to prevent a crushing or destructive pressure of the roller upon the gelatin band. As the platen roller is swung downwardly it first engages the grip roller with the sheet therebetween and finally reaches the impression position shown in Fig. 5 below the axis of the grip roller and in operative relation to the gelatin band. It is necessary to maintain this engagement of the platen roller with the grip roller in order to feed the sheets to the gelatin band on the impression stroke of the carriage and also to strip the sheet from the band on the return stroke of the carriage. This is accomplished by the cam action of the walls of the bearing slots 100' in the platen yoke, as shown more clearly in Fig. 6a. These slots are disposed at such an angle that their cam walls 101' constantly bear against the

platen roller shaft, and the downward pressure on the platen yoke by the operator constantly urges the platen roller into operative contact with the grip roller and with the gelatin band. This cam action overcomes any tendency of the platen roller to separate from the grip roller on the impression stroke or on the return stroke of the carriage, which might adversely affect the feeding or stripping of the sheet. The angle of the cam slots permits the platen roller to yield when it is brought into engagement with the grip roller but causes positive pressure to be applied to the platen roller during the impression and return strokes of the carriage. Hence the spring 104 need be only of sufficient strength to yieldingly hold the platen roller in the ends of the slots while the platen roller is being moved into or out of impression position.

20 A guard plate 106 is fastened to the platen yoke and extends over the brake and prevents damage to the brake as well as serving to prevent a sheet from getting under the brake.

When the operator starts the carriage rearwardly along the bed plate for the impression operation the sheet is fed between the platen and grip rollers and laid upon the gelatin surface. The sheet adheres to the gelatin band and the platen roller is rotated by contact with the sheet to press the sheet smoothly upon the gelatin band. At the beginning of the movement of the carriage, however, Fig. 5, the sheet has not sufficient area of contact with the gelatin band to cause it to adhere to said band, and to prevent the rollers from dragging the sheet away from the margin bar before sufficient contact is made with the gelatin roll, which would destroy registration of the sheet with respect to the gelatin band, I provide means for initially insuring positive and immediate rotation of the platen roller at the instant the carriage starts on its impression stroke. In the structure shown in the drawings this means consists of a block 45 of rubber or other suitable friction material 107 which is engaged by an extension 100 on the end of the platen roller when it is in its lowered position. This block is carried at the end of a spring member 108 which is fastened to the bed plate frame and causes the platen roller to commence rotating instantly the carriage is started in motion. This block is sufficiently long to overlap a portion of the gelatin band in the direction of movement of the carriage so that by the time the platen roller leaves the block the sheet will have sufficient contact and adherence with the gelatin band to prevent it moving or shifting out of registration. It has been found in practice that regardless of the speed at which the carriage is started in motion the instant initial rotation of the platen will hold the sheet registered against the margin bar.

65 I provide means for automatically moisten-

ting or wetting the gelatin band as it is being re-wound upon the gelatin roll on the conveyor. Referring to Figs. 2 and 11 it will be seen that there is a water pan or trough 115 mounted in the main frame directly below the gelatin band roll which is in operative position. The pan contains water to about the level indicated by dotted lines 116. A transfer roller 117 is rotatably mounted in this trough in position to constantly dip into the water in said trough. A second or moistening roller 118 is arranged parallel with the transfer roller 117 and is rotatably mounted in the ends of links 119, the other ends of which links are pivotally connected to the arms 120. The arms 120 are mounted on the transfer roller shaft 121. This shaft has an upright arm 122 at one end adjacent the side member 3 of the main frame. One end of a coil spring 123 is connected to arm 122 and its other end is connected to an arm 124 pivotally mounted in the side member 3 of the main frame. This arm is operated by a finger lever 125 on the outside of the main frame, and when said lever is swung about its pivot the spring is lengthened and the tension of the spring on the arm 121 urges the moistening roller 118 upwardly, maintaining the moistening roller in contact with both the gelatin band roll and the transfer roller. The moistening roller automatically follows the varying diameter of the gelatin roll and uniformly moistens the entire surface of the gelatin band as it is wound upon its spindle. The moistening roller may if desired remain in contact with the gelatin roll whether it is being unwound from its roll or rewound upon it. It is preferable, however, to throw the moistener into contact with the gelatin roll only when the band is being rewound. I use a long coil spring 123 so that the tension on the arm 121 will be substantially uniform throughout its range of movement and the pressure of the moistener roll on the gelatin band roll will be substantially uniform regardless of its diameter. The moistener roller is preferably covered with felt or other suitable absorbent which will readily absorb the moisture from the transfer roller and carry it to the gelatin band. The ends of the shaft 126 of the moistener roller project beyond the links 119 in position to engage the notched rest holders 127 which are secured to the inner end walls of the water pan Fig. 11. These rest holders are positioned to prevent the moistener roller from dropping, when the tension on the spring 123 is relieved, to the bottom of the pan which may have an accumulation of dirt therein. When the moistener roller is in the rest holders it will be out of contact with the gelatin roll. It will, however, dip into the water as shown in dotted lines in Fig. 11 sufficiently so that it will carry water to the gelatin roll at the start and until the trans-

fer roller has revolved sufficiently to carry water to said moistener roller.

At the rear end of the machine I provide a work shelf for the operator, upon which the sheets may be stacked in convenient position. This shelf Figs. 1 and 14 is a flat table 130 supported horizontally above the frame and bed by a U-shaped bar or frame 131 of tubular construction. The frame has a long leg 132 which is swiveled at one of the rear corners of the main frame whereby the table or shelf may be swung laterally to a position clear of the bed of the machine if desired. The other leg 133 which is relatively short is arranged to engage the crowned end plug 134 projecting from the end of an extension 135 upstanding from the other rear corner of the frame. When thus engaged the table frame is held or locked in a fixed position, but by springing the frame upwardly so that the end of the leg 133 clears the crowned plug 134 the table may be swung to any desired position.

The swivel connection of leg 132 is formed by inserting it in an opening 136 in the upper edge of the side member 3 of the main frame and placing the end of the leg over the head of the bolt 137 which fastens the frame member 3 to the upper end of main frame leg 1. The extension 135 is mounted in the other rear corner of the main frame in the same manner as just described. This construction provides a simple but efficient mounting for the shelf and permits the shelf and its frame to be readily dismounted for shipping purposes.

I am aware that changes in the form, construction and arrangement of parts of my invention may be made without departing from the spirit or sacrificing the advantages of the invention and I reserve the right to make all such changes as fairly fall within the scope of the following claims:

I claim:

1. In a machine of the class described the combination of a frame having a bed, a gelatin band on the bed adapted to receive a sheet to be printed, a platen roller movable over said sheet and adapted to be rotated by contact therewith, and a friction block on the frame at one side of the band and adapted to be engaged by the platen roller at one end thereof in its initial position for impression travel to insure rotation of the roller when it begins its travel and thereby prevent displacement of the sheet.

2. In a machine of the class described the combination of a frame having a bed, a gelatin band on the bed adapted to receive a sheet to be printed, a margin bar across the front end of the bed, a platen roller movable over said sheet and adapted to be rotated by contact therewith, an extension on the platen roller at one end thereof, and a friction member mounted on the frame adjacent the mar-

gin bar and at one end thereof and adapted to be engaged by said extension in the initial position of the platen roller for impression travel to insure rotation of the roller when it begins its travel and thereby prevent displacement of the sheet.

3. In a machine of the class described the combination of a frame having a bed, a gelatin band on the bed, a platen roller movable along the bed, means for raising and lowering said platen roller with respect to said band, a spring bearing on the platen roller for retarding the rotation of said platen roller while it is being lowered, and a stop adapted to engage and release the spring from the platen roller as the platen roller reaches its lowered position.

4. The combination of a frame having a bed, a gelatin band on said bed, a margin bar adjacent one end of said bed, a carriage movable along the bed towards and from the margin bar, a platen roller mounted on said carriage and adapted to be raised and lowered with respect to said band, a brake for holding the platen roller against rotation while being lowered, and means operable when the platen roller is lowered adjacent said margin bar for imparting rotation to the platen roller upon movement of the carriage away from the margin bar.

5. The combination of a frame having a bed, a gelatin band on said bed, a margin bar adjacent one end of said bed, a carriage movable along the bed towards and from the margin bar, a platen roller mounted on said carriage, means for raising and lowering the platen roller with respect to said gelatin band, a brake for holding the platen roller against rotation while being lowered, means for releasing said brake before the platen roller reaches its lowered position, and means engageable by an extension on the roller operable when the platen roller is lowered adjacent said margin bar for imparting rotation to the platen roller upon movement of the carriage away from the margin bar.

6. The combination of a frame having a supporting bed and a gelatin band thereon, a movable carriage, a platen roller on the carriage, a transverse margin bar for the sheet to be printed at one end of the bed, side bars supporting the margin bar and slidably arranged on the frame, said side bars having notches therein, and studs on the frame engaging said notches to retain the margin bar in sheet receiving position.

7. The combination of a frame having a supporting bed and a gelatin band thereon, a movable carriage, a margin bar at the front of the bed, a platen roller on said carriage adapted to be moved to a position beyond the end of the bed to overlie the margin bar, and a yielding friction member on the frame at one side of the gelatin band to en-

- gage and rotate the platen when the carriage moves.
8. The combination of a main frame having a bed and a gelatin band thereon, a yoke pivotally mounted above the bed, a relatively fixed grip roller, a platen roller movably mounted on said yoke, and cam means for holding said platen roller in operative relation to said grip roller when the yoke is swung downward to carry the platen roller to impression position.
9. The combination of a main frame having a bed and a gelatin band thereon, a carriage arranged to travel above the bed, a relatively fixed grip roller and a movable platen roller supported on the carriage, cam means associated with said platen roller, and manually operated means cooperating with said cam means for maintaining the platen roller in operative relation to the grip roller during the travel of the carriage through impression position.
10. The combination of a frame having a bed and a gelatin band thereon, a carriage adapted to travel along said bed, a relatively fixed grip roller on said carriage, a platen roller, a movable member on said carriage supporting the platen roller, and cams actuated by said member for forcing the platen roller into operative relation with the grip roller during the travel of the carriage through impression position.
11. The combination of a frame having a bed and a gelatin band thereon, a carriage, a yoke pivoted on the carriage, said carriage being movable above said bed by manual pressure applied by the operator on the yoke, a relatively fixed grip roller and a movable platen roller on said carriage, and means operated by the pressure on the yoke for maintaining the platen roller in operative relation to the grip roller and the gelatin band as the carriage travels through impression position.
12. The combination of a frame having a bed and a gelatin band thereon, a carriage adapted to travel above said bed, a relatively fixed grip roller on said carriage, a yoke pivoted on said carriage, means for applying pressure to the yoke to move the carriage, a movable platen roller in said yoke, and cam means operated by the pressure on the yoke for maintaining the platen roller in operative relation to the grip roller and the gelatin band during the travel of the carriage through impression position.
13. The combination of a main frame having a bed and a gelatin band thereon, a yoke pivotally mounted above the bed, a relatively fixed grip roller, said yoke having slots therein and said slots being arranged to form cams, and a movable platen roller mounted in said cam slots and held thereby in operative relation to said grip roller when the yoke is swung to carry the platen roller to impression position.
14. The combination of a frame having a bed and a gelatin band thereon, a carriage arranged to travel above the bed, a relatively fixed grip roller on the carriage, a yoke pivotally mounted on the carriage, said yoke having slots therein and said slots being arranged to form cams, and a movable platen roller mounted in said cam slots and held thereby in operative relation to said grip roller while the carriage is traveling through impression position.
15. The combination of a bed, a carriage movable along said bed, a platen roller, a yoke pivoted on said carriage to swing towards and from the bed and having bearing slots disposed angularly with respect to the line of movement of the carriage when the yoke is in lowered position, said bearing slots acting as cams to force the platen roller towards the bed as the carriage moves, and springs yieldingly holding the platen in the ends of said slots when the yoke is swung away from the bed.
16. The combination of a frame, a bed, a winding reel at one end of said bed, a conveyor in said frame carrying a plurality of gelatin band rolls and adapted to bring the rolls into operative position at the other end of the bed, the band of the roll in operative position being adapted to be stretched over the bed and connected to said reel, driving means for operating said reel to wind the band thereon, and a shaft extending to said positioned roll and operated by said driving means for actuating the positioned roll to rewind the band thereon.
17. The combination of a frame, a bed, a winding reel at one end of said bed, a conveyor in said frame carrying a plurality of gelatin band rolls and adapted to bring the rolls into operative position at the other end of the bed, the band of the roll in operative position being adapted to be stretched over the bed and connected to said reel, means common to both the positioned roll and the reel for winding the band from one to the other, a shaft extending from said common means to said positioned roll, and means for operatively connecting said common means to or disconnecting it from said reel or said shaft.
18. The combination of a frame, a bed, a winding reel at one end of said bed, a conveyor in said frame carrying a plurality of gelatin band rolls and adapted to bring the rolls into operative position at the other end of the bed, the band of the roll in operative position being adapted to be stretched over the bed and connected to said reel, means for driving either the positioned roll or the reel to wind the band from one to the other, and means for operatively connecting said driving means to the one and disconnecting it from the other.
19. In a machine of the class described, the combination of a gelatin band roll, means

- for winding and unwinding the roll thereby varying its diameter, a liquid container below said roll, a transfer roller revolvable in the liquid, a moistening roller, and means yieldingly maintaining said moistening roller in contact with the gelatin roll and the transfer roller.
20. In a machine of the class described, the combination of a gelatin band roll, means for 10 winding and unwinding the roll thereby varying its diameter, a liquid container below said roll, a transfer roller revolvable in the liquid, a moistening roller, means yieldingly maintaining said moistening roller in contact with the gelatin roll and the transfer 15 roller, means operable at a distance for releasing the moistening roller from contact with the gelatin band, and means supporting said moistening roller out of contact with the 20 gelatin roll in the container when it is released.
21. The combination of a frame, a printing bed, a conveyor, a plurality of gelatin band rolls carried by said conveyor, means for operating said conveyor in one direction to bring said rolls individually into operative 25 position relative to said bed, and a latch on the frame arranged in the path of the conveyor and adapted to lock the conveyor with a roll in operative position, said latch permitting the conveyor to overrun and also permitting reverse movement of the conveyor to set the roll in operative position.
22. The combination of a frame, a printing bed, a conveyor having a plurality of spindles thereon, gelatin band rolls on said spindles, an operating shaft in said frame, a gear on each spindle adapted to be brought into driving 30 relation to said shaft when its roll is arranged in operative position, and means for driving said shaft.
23. The combination of a frame, a bed, a conveyor in said frame carrying a plurality of gelatin band rolls, means for moving said conveyor whereby the rolls thereon are sequentially moved into an operating position so that the gelatin band of the roll at operating position may be directed over the bed to provide an impression surface, and means 45 for positioning said rolls in said operative position including members having stop shoulders thereon whereby a roll may be moved past said members and then moved in the reverse direction to engage said stop shoulders 50 to be positioned in said operating position.
24. The combination of a frame, a bed, a conveyor in said frame carrying a plurality of gelatin band rolls, means for moving said conveyor whereby the rolls thereon are sequentially moved into an operating position so that the gelatin band of the roll at operating position may be directed over the bed to provide an impression surface, pivotally mounted pawls having tapered surfaces 55 thereon whereby as said rolls move into operating position said pawls may be cammed upwardly by engagement of said rolls with said tapered surfaces to permit said rolls to be freely moved thereby, said pawls having stop shoulders thereon whereby after one of said rolls has been moved past said pawls it may be moved in the opposite direction to engage said stop shoulders to be accurately positioned in operating position.
25. The combination of a frame, a bed, a conveyor in said frame carrying a plurality of gelatin band rolls wound on spindles, means for imparting movement to said conveyor whereby said gelatin band rolls may be sequentially moved into and through an operating position, the gelatin band of the roll at operating position being withdrawn therefrom and directed across said bed to provide an impression surface, and pivotally mounted stop pawls having tapered surfaces thereon whereby as the spindles of said rolls move into operating position said spindles will engage said tapered surfaces to move said pawls out of the path of movement of said spindles, said pawls having recesses therein providing stop shoulders whereby after the spindles of said rolls have been moved past said pawls said conveyor may be moved in the opposite direction whereby the spindle of the roll to be disposed at operating position will move into said recesses in said pawls to engage said stop shoulders to be positioned at operating position.
26. In a duplicating machine, a bed having a gelatin impression surface thereon, a carriage movable over said gelatin impression surface for taking impressions therefrom and including a carriage bar, a sheet feed chute adjustably mounted on said carriage bar, a carriage yoke pivotally connected to said chute, releasable means for holding said yoke in a definite position relative to said chute and bar, a grip roller rotatably mounted in said yoke, a substantially U-shaped frame pivotally mounted in said yoke, a platen roller mounted in said U-shaped frame, and a handle for pivoting said frame whereby said platen roller may be moved relative to said grip roller and said impression surface to apply a sheet passed through said sheet feed chute to said impression surface.
27. A duplicating machine including a bed having a gelatin impression surface thereon, a carriage, means supporting said carriage for movement over said bed and said impression surface, said carriage including a depending arm, a guide bar mounted at the side of said bed, a bracket mounted on said depending arm, and rollers in said bracket and arranged on opposite sides of a vertical plane through said guide bar and in diametrical opposition to each other and adapted to travel along said guide bar to rigidly 120
- 125
- 130

hold the carriage square with said impression surface.

28. A duplicating machine including a bed having a gelatin impression surface thereon, 5 a carriage, means supporting said carriage for movement over said bed and said impression surface, said carriage including a depending arm, a guide bar mounted at the side of said bed, a sheathing providing a bearing 10 surface about said bar to deaden noise and obviate the necessity of lubrication, a bracket mounted on said depending arm, and rollers in said bracket and arranged on opposite sides of a vertical plane through said guide 15 bar, and in diametrical opposition to each other and adapted to travel along the sheathing about said guide bar to rigidly hold the carriage square with said impression surface.
